UNITED STATES PATENT OFFICE

2,536,026

CENTRIFUGAL PUMP

Calvin M. Bolster, United States Navy

Application April 12, 1945, Serial No. 588,052

16 Claims. (Cl. 103—109)

(Granted under the act of March 3, 1883, as amended April 30, 1928; 370 O. G. 757)

1

This invention relates to centrifugal pumps and it has a particular relation to pumps of the multi-stage type.

The principal object of the invention is the provision of a centrifugal pump in which the diameter of the pressure chamber or container is only a fraction of the effective diameter of the pump rotors or impellers about their common axis of rotation which results in a great reduction in weight and wall thickness of the chamber for any given pressure.

Another object of the invention is the provision of a pump embodying a plurality of oppositely rotating rotors for causing a direct flow of the fluid through successive stages with a resultant multi-stage arrangement in a relatively small volumetric space.

A further object of the invention is the provision of a pump of the character described in which the several oppositely rotating impellers move about instantaneously fixed centers of rotation located in the circumferences thereof, whereby the flow of fluid from one impeller to another caused by centrifugal force will be in a direction diametrical of the impeller from such instantaneous fixed point of rotation to a circumferentially disposed point diametrically opposite thereto and the flow of fluid through adjacent impellers being in opposite directions notwithstanding the rotation of the several impellers about their common axis.

Still another object of the invention is the provision of a centrifugal pump embodying one or more units mounted for revolution about a common axis and each having a plurality of coaxially arranged oppositely rotating impeller elements or rotors the arrangement being such that the centrifugal force generated by the several impellers is accumulative as the fluid passes from stage to stage.

A still further object of the invention is the provision of a pump wherein the radial travel of the medium being pumped is extremely small although the velocity and pressure rise is relatively great.

Another object of the invention is the provision of a centrifugal pump embodying a plurality of individual pump units arranged symmetrically about a central shaft and connected in series whereby a high number of pressure stages may be employed within a relatively small space.

Still another object of the invention is the provision of a centrifugal pump embodying a plurality of centrifugal pump assemblies

2

mounted for revolution about a common central axis and which are adjusted radially with respect to said axis so as to obtain a variable pressure delivery with any given rate of rotation.

5 In order to make the invention more clearly understood there are shown in the accompanying drawings, means for carrying the invention into practical effect, without limiting the improvements in their useful application to the particular constructions and arrangements which, for the purpose of explanation, have been made the subject of illustration.

In the accompanying drawings:

15 Fig. 1 is a side elevational view of multi-stage centrifugal pump constructed in accordance with the invention;

Fig. 2 is an end elevational view of the pump structure shown in Fig. 1 as viewed from the delivery or right hand end of Fig 1;

20 Fig. 3 is an enlarged view partly in plan and partly in horizontal step section taken substantially on the line 3—3 of Fig. 2;

Fig. 4 is a vertical transverse sectional view through the pump units taken on line 4—4 of Fig. 1;

25 Fig. 5 is a view similar to Fig. 4 but taken on line 5—5 of Fig. 1;

Fig. 6 is an enlarged fragmentary vertical longitudinal sectional view of both ends of the pump;

30 Fig. 7 is an enlarged fragmentary transverse sectional view of the pressure varying mechanism taken on line 7—7 of Fig. 1;

Fig. 8 is an exploded perspective view of one of the impeller or rotor mechanisms of the pump;

35 Fig. 9 is a diagrammatic end elevational view of a centrifugal pump constructed with five inter-communicating pump units;

40 Figs. 10 and 11 are vector diagrams illustrating the diametrical flow of the fluid medium through the oppositely rotating impellers of the pump.

Fig. 12 is a diagrammatic view of two adjacent impellers or rotors circumferentially offset relative to one another and illustrating the diametrical flow of the fluid medium under centrifugal action when the impellers are moved about an instantaneous fixed point in space.

45 Fig. 13 is a longitudinal cross sectional view illustrating a modified form of the invention.

Fig. 14 is a cross sectional view taken on the line 14—14 of Figure 13 and

50 Figs. 15 and 16 illustrate diagrammatically still further modified forms of the invention.

Referring to the drawings, the present invention comprises three or more housings 10, each provided with axially aligned trunnions or stud shafts 11 and 12 disposed eccentrically with respect to the housing at opposite ends thereof which are pivotally mounted in bearings 13 and 14 on arms 15 and 16 of spiders 17 and 18. Each of the bearings 13 and 14 are provided with double shaft seals 19 and 20 respectively. These spiders are formed on the ends of the main shafts 21 and 22 which are journaled in main bearings 23 and 24 carried by end supporting castings 25 and 26 formed on or secured to a base plate 27.

One end of each of the housings 10 is formed with an integral head 28, provided with a shaft seal 29 and the other is closed by a removable head 30, provided with a shaft seal 31. Rotatably mounted within a bore 32 of the housing 10 is an impeller cage 33 (see Figs. 3 and 8) which contains a plurality of alternately arranged oppositely rotatable impellers 34 and 35. The impellers 35 on the other hand have smooth peripheries and are free to rotate independently of the cage 33 and the impellers 34, and comprise a wall 35a, blades 35b and keys 38 formed in hubs 39 thereof. The keys 38 are adapted to engage a keyway 40 formed in the shaft 41 so as to rotate therewith. The impellers 35 on the other hand have smooth peripheries and are free to rotate independently of the cage 33 and the impellers 34, and comprise a wall 35a, blades 35b and keys 38 formed in hubs 39 thereof. The keys 38 are adapted to engage a keyway 40 formed in the shaft 41 so as to rotate therewith. This shaft extends coaxially through the housing and is journaled intermediate its end in a friction-less bearing 42 mounted in the integral head 43 of the impeller cage and has keyed thereto a gear 44 which is held against displacement by a lock nut 45. The other end is journaled in a friction-less bearing 46 mounted in a removable driving head 47 of the impeller cage. The driving head 47 forms an end closure for the impeller cage and is keyed thereto by peripheral tongues or keys 48 which project into the slots 37 thereof and is adapted to drive the impeller cage and its associated impellers 34 independently of the impellers 35. This driving head is provided with a boss 49 which is journaled in the removable head 30 (a friction-less bearing may be provided at this point) and is further provided with a stud shaft 50 which extends through the shaft seal 31 and has keyed thereto a gear 51 which is held in place thereon by a lock nut 52.

A gear 53 mounted for free rotation upon the trunnion or stud shaft 12 and held thereon by a lock nut 55 is adapted to mesh with a stationary sun gear 56 mounted on the end supporting casting 26 and forms in part the driving medium for the impellers 35. Idler gears 57 and 58 mounted on a stud shaft 59 journaled in a bearing 60 cast integral or otherwise secured to the head 28 of the housing 10 are provided and complete the gear train between the impeller gear 44 and the sun gear 56.

A gear 54 mounted for free rotation upon the trunnion or stud shaft 11 and held thereon by a lock nut 61 is adapted to mesh with a stationary ring gear 62 mounted in the end supporting casting 25 and forms in part the driving medium for the impeller cage 33 and its associated impellers 34. Idler gears 63 and 64 mounted on a stud shaft 65 journaled in a bearing 66 cast integral or otherwise secured to the removable head 30 of the housing 10 are provided and complete the gear train between the impeller cage 33 and the ring gear 62.

The pumped medium enters the pump through a central bore 67 in the main shaft 21 and travels radially outward through passages 68 formed in the arms 15 of the spiders 17, thence to the pump housing 10 through a passage 69 where it is directed to the first stage of the impeller cage 33. The medium then passes through the impeller 35 through volute passage 70 thence through impeller 34 to volute passage 71 positioned diametrically opposite volute 70. This procedure is continued until the medium reaches the center of the pump housing where it is directed through a passage 72 to the extreme right of the impeller cage and the same procedure takes place only in a reverse direction, i. e., the medium is forced to travel under pressure from right to left toward the center of the housing where it emerges into passage 73 thence to radial passages 74 formed in the arms 16 of the spider 18 to central bore 75 in the main shaft 22 where it emerges under high pressure.

As shown, the flow through the stages is so arranged that the end thrust on the separating walls of the impellers 34 and 35 is equalized and there is no net thrust.

It will be readily understood from the foregoing description and particularly from Figure 3 of the drawings that the arrangement of shaft seals will prevent any possibility of leakage of the pumped medium, thereby providing a closed system essential to the operation of such a pump.

With the impeller driver gears 53 and 54 in mesh with the stationary sun and ring gears 56 and 62 secured to the supporting castings 25 and 26, and the assembly thus described, rotated rapidly as a unit by means of a gear 76 fixed to the main shaft 21 driven by any suitable prime mover, the housings 10 will revolve in an orbit about the axis of the main shafts 21 and 22 and the impellers 34 and 35 mounted therein will rotate at high speed in opposite directions with respect to one another simultaneously with the revolution of the housings, thereby attaining a high peripheral velocity with resultant high pressure head due to centrifugal action, while keeping the diameter and weight of the pressure vessels to a minimum.

Principle of operation

As shown diagrammatically in Figure 10, as crank and rotating pump housing C rotates in a counter-clockwise direction about center A; rotor R₁ rotates in a counter-clockwise direction about center B, being driven by a gear which meshes with a fixed gear G₁ at point D. It will be evident that the peripheral velocity of the rotor or impeller R₁, at point D, in space, is zero since at this point it is held fixed by the meshing gear. Thus, if crank C has a peripheral velocity V₁ at D, the velocity of the rotor R₁ will have no pressure. Point D thus becomes the instantaneous center of rotation of the pumped medium. At point B the rotor speed and peripheral velocity V₃ equals the pump housing velocity at that point. At point F the rotor velocity in space equals the sum of its own velocity V₂ about center B plus the velocity V₄ of the pump housing at point F, about center A. Thus a pumped medium at point F has an instantaneous velocity equal to the sum of velocities about centers A and B at radius AF, namely V₂ plus V₄. It will be evident that there will be a flow of the pumped medium with a resultant increase in pressure from point D to F.

As shown in Figure 11, as crank and rotating

pump housing C rotates in a counter-clockwise direction about center B, being driven by a gear which meshes with a fixed gear G₂ at point F. It will be evident that the peripheral velocity of the rotor or impeller R₂ at point F will be zero since at this point it is held fixed by the meshing gear. Thus, if crank C has a peripheral velocity V₄ at F, the velocity of the rotor R₂ at F will be equal and opposite to it or V₅ and at F, rotor R₂ will have no pressure. It thus becomes comparable to the instantaneous center of rotation of a pumped medium at point F. At point B the rotor speed and peripheral velocity equals the pump housing velocity V₃ at that point. At point D in instantaneous velocity of the rotor equals the sum of its own velocity V₅ plus the velocity V₁ of crank housing at point D. Thus a pumped medium at point D has an instantaneous velocity equal to the sum of velocities about centers A and B at radius AD, namely V₁ plus V₅. It will be evident that there will be a flow of pumped medium with a resultant increase in pressure from F to D.

Figure 12 is a diagrammatic showing of two adjacent impellers or rotors circumferentially offset relative to one another and illustrating the diametrical flow of the fluid medium under centrifugal action when the impellers are moved about an instantaneous point in space.

Thus if the rotors or impellers are alternately arranged to rotate in opposite directions it will be evident that a continuous flow and pressure increase will occur, the pump medium passing from one rotor to the next through suitable passages in the revolving housing where the pumped medium is subject to the pressure caused by the revolution of the housing itself plus that received from the preceding rotor stage.

Multi-stage pump arrangement

In order to obtain proper balance it will be desirable to arrange several housing assemblies with their rotors or impellers about the center of rotation of the housings. These rotors may all be driven by the same fixed gears and with their housings they make possible a compact arrangement for many stages. If placed in series the pumps will deliver high pressure on a relatively light weight and small overall size. Such an arrangement of housing assemblies is shown schematically in Figure 9, wherein the impeller housings 100 are supported on spiders 101 mounted on a main shaft 102 journalled in main bearings 103 carried by end supporting castings 104 and 105. Each of the impeller housings are provided with a plurality of alternately arranged oppositely rotatable impellers similar to the impellers 34 and 35 and are driven by gears 106 arranged on opposite ends of the impeller housings which mesh with the stationary sun and ring gears 107 and 108 carried by the end supporting castings. Fluid is admitted to the pump through a central bore in the main shaft thence to one of the impeller housings through duct 109. The impeller housings are connected in series and the fluid under pressure is transferred from one impeller housing to the next by means of ducts 110, thence out through duct 111 which is in communication with a central bore in the opposite end of the main shaft 102.

A more elaborate arrangement of this type of pump makes possible a variation in pressure at any given speed, thus enabling the construction of a variable pressure constant speed centrifugal pump which is shown and described as the pre-

ferred embodiment of the invention. To accomplish this result it is only necessary to provide a means whereby the radius of rotation of the impeller assemblies about the main shafts can be varied. Wherein the impellers 34 and 35 with their housings 10 are arranged to move through a limited arc about center x while the entire assembly rotates about the main shafts 21 and 22. The fixed gears 56 and 62 drive the impellers through drive gears 53 and 54 and their associated gear trains so that the resultant rotation of the impellers remains constant even though the radius of rotation of the impellers relative to the main shafts 21 and 22 is changed. It will be apparent that as the radius of rotation of the impeller housings about the main shafts is decreased or increased at any given R. P. M., there will be a resultant decrease or increase in delivery pressure.

The mechanism employed to vary the orbital path of the impeller housings 10 about the main shaft is illustrated to advantage in Figures 5 and 6 of the accompanying drawings, and includes an operating handle 77 which is pivoted at 78 to the end supporting casting 25 of the pump assembly and has mounted thereon a manually operated pawl 79 adapted to engage a segment 80 cast integral with the pivot 78 and together provide means whereby the adjustment mechanism can be locked in any desired position. A yoke 81 pivoted at 82 to the end supporting casting is provided with arms 83 which are connected to the operating handle by means of a link 84 and is further provided with depending arms 85 adapted to straddle a grooved collar 86 formed on the outer end of a slideable sleeve 87 splined to the main shaft 21. The slideable sleeve 87 has formed therein spiral slots 88 which are adapted to engage trunnions 89 carried by the hub 90 of a spur gear 91 and provides a loose coupling between the slideable sleeve 87 and the spur gear 91 which permits free movement of the parts relative to one another irrespective of their rotary motion. A slip ring 92 fits within the groove of the collar 86 and is provided with trunnions 93 which are journalled in the ends of the depending arms 85 of the yoke 81. Segmental gears 94 adapted to mesh with the spur gear 91 are keyed to shafts 95 journalled in bearings 96 formed on the spiders 17 and 18. The shafts 95 are further provided with arms 97 which are connected to the housings 10 at 98 through links 99.

From the foregoing description it will be readily understood that any movement of the operating handle will cause the slideable sleeve to move laterally along the main shaft and by cam action exerted on the trunnions carried by the spur gear through the spiral slots in the slideable sleeve will advance or retard the spur gear relative to the main shaft causing the segmental gears and their associated shafts to rotate, and through the links coupling the shafts with the impeller housings the latter will move radially outward or inward dependent on the direction of movement of the operating handle, thereby varying the radius of revolution of the impeller housings and the fixed points about the main shaft.

With the arrangement of parts thus described it will be evident that any adjustment varying the orbital path of the impeller housings will be synchronized to keep the rotating members in proper alignment and that such adjustment can be made at the will of the operator without interfering with the speed of the pump.

The pump housing illustrated in Figures 13 and

14 includes the essential details provided in Figure 3 of the preferred form of the invention and comprises an impeller cage 120 having a plurality of ports 121 therein adapted to register with the fluid ducts provided in the housing. The impeller cage is mounted within the central bore of the housing and is locked against rotation by any suitable means. Mounted for free rotation within the impeller cage there is provided a plurality of impellers 122 spaced apart by discs 123 having a fluid passage 124 therethrough, the impellers 122 are keyed to a shaft 125 and are adapted to rotate therewith while the discs are held against rotation by the engagement of the projections 126 formed on the peripheries thereof with the longitudinal slots 127 provided in the impeller cage.

The modified pump illustrated in Figure 15 reduces the pump to its simplest form and comprises but a single impeller 128, and the form in Figure 16 comprises a duplication of the structure illustrated in Figure 15.

It will be understood, that the above description and accompanying drawings comprehend only a general embodiment of the invention and that various changes in the construction, proportion, arrangement and general combination of parts may be made without departing from the spirit and scope of the invention. The present embodiments are therefore to be considered in all respects as illustrative and not restrictive, the scope of the invention being indicated by the appended claims rather than by the foregoing description, with all changes falling within the scope, meaning and range of equivalency of the claims intended to be embraced therein.

The invention described herein may be manufactured and used by or for the Government of the United States of America for governmental purposes without the payment of any royalties thereon or therefor.

What is claimed is:

1. A multi-stage variable pressure rotary pump including in combination a plurality of centrifugal pump units each comprising a housing having a pressure chamber therein and provided with a fluid inlet and a fluid outlet; a machine frame; a suspension shaft revolvable therein; a suction conduit and a discharge conduit formed in said suspension shaft; a pair of spaced spider members formed integral with said shaft; axially aligned bearings formed in said spiders; the legs of said spider members having formed therein radial fluid passages interconnecting said fluid inlets and said fluid outlets in said pump housings with said suction conduit and said discharge conduit in said suspension shaft; said pump housings each provided with axially aligned trunnions eccentrically disposed thereto and journalled in said bearings in said spiders; an impeller cage rotatably mounted in each of said pressure chambers; said impeller cages having a plurality of ports formed therein; a driving head coupled to each of said impeller cages at one end thereof; a stud shaft formed thereon; a gear keyed to each of said stud shafts; an impeller shaft coaxially mounted in each of said impeller cages having one end extended through the other end of said impeller cages and pump housings; a gear keyed to each of said impeller shafts; a plurality of impellers mounted in each of said impeller cages and forming a series of intercommunicating pressure stages; certain of said impellers being keyed to said impeller cages for rotation therewith, the others being keyed to said impeller

shafts for rotation therewith within said impeller cages; a stationary ring gear mounted in said frame concentric with respect to said suspension shaft; a gear train connecting said impeller cage gears with said ring gear; a stationary sun gear mounted on said frame concentric to said suspension shaft; a gear train connecting said impeller shaft gears with said sun gear; means for rotating said suspension shaft to cause said pump units to revolve therewith, whereby to cause said impellers, through their respective gear trains in mesh with said stationary ring and sun gears, to rotate about their axis in each pressure chamber in opposite directions during their revolution about the axis of said suspension shaft to induce fluid admitted into said pressure chambers through said suction conduit to flow from stage to stage through said pump units toward said discharge conduit with progressively increasing pressure; and means for adjusting the radial displacement of said pump units from the axis of said shaft by turning them about their trunnion bearings to vary the pressure of the fluid medium delivered from said pump units independently of the speed of operation.

2. A multi-stage variable pressure rotary pump including in combination a plurality of centrifugal pump units each comprising a housing having a pressure chamber therein and provided with a fluid inlet and a fluid outlet; a machine frame; a drive shaft including suspension means revolvable therein; said pump units being eccentrically journalled in said suspension means in annularly spaced relation about the axis of said shaft; means for rotating said shaft with said pump units; a plurality of pairs of impellers mounted in each of said chambers and forming a series of intercommunicating pressure stages; means driven by said rotating means for moving the impellers of each of said pairs in opposite directions about a common axis in each of said chambers to cause fluid admitted into said chambers through said inlets to flow from stage to stage through said pump units toward said outlets with progressively increasing pressure; and means for adjusting said pump units on their eccentric journals to vary the pressure of the fluid medium delivered from said pump units, comprising a sliding sleeve having spiral slots formed therein splined on said drive shaft; a spur gear mounted for free rotation on said shaft; a hub formed on said spur gear having a central bore therein adapted to receive said sleeve; trunnions carried by said hub adapted to fit within said spiral slots in said sleeve; a shaft for each pump unit carried by said suspension means; segmental gears keyed to one end of said shafts meshing with said spur gear; radially extending arms integral with said shafts; a pair of arms formed integral on said pump housings; links connecting said arms of said pump housings to said arms on said shafts; a grooved collar formed on the outer end of said sliding sleeve; a yoke pivoted to said frame adapted to straddle said grooved collar; a slip ring fitted within said groove in said collar; trunnions carried by said slip ring adapted to be journalled in the ends of said yoke; a pair of upwardly extending arms formed on said yoke; an operating handle pivoted on said frame; a link connecting said upwardly extending arms of said yoke to said operating handle, and locking means for said operating handle and said adjusting means.

3. A centrifugal pump comprising a rotatable housing having an impeller chamber eccentrically

located therein, an impeller rotatably mounted in said chamber and having radial passages connected together at their inner ends, pump inlet and outlet passages in said housing connected to the periphery of said chamber in each of the halves thereof respectively which are opposed to each other in a radial direction with respect to the axis of rotation of said housing, driving means for rotating said housing, connections from said driving means for rotating said impeller, whereby a centrifugal pressure differential is obtained at the periphery of said halves of said chamber, causing a flow from said inlet passage to said outlet passage.

4. A centrifugal pump as defined in claim 3, wherein said housing and impeller are driven in the same direction for causing a radially outward flow through said impeller with respect to the axis of rotation of said housing.

5. A centrifugal pump as defined in claim 4, wherein said connections comprise a stationary sun gear mounted on the axis of rotation of said housing, and a planetary gear mounted for rotation with said impeller and meshing with said stationary sun gear.

6. A centrifugal pump as defined in claim 3, wherein said housing and impeller are driven in opposite directions for causing a radially inward flow through said impeller relative to the axis of rotation of said housing.

7. A centrifugal pump as defined in claim 6, wherein said connections comprise a stationary internal ring gear, and a planetary gear mounted for rotation with said impeller and meshing with said internal ring gear.

8. A centrifugal pump as defined in claim 3, wherein said housing is hingedly mounted on a rotatable support, and means for adjusting the housing about said hinge to vary the radial displacement of said impeller relative to the axis of rotation of said support and thus cause a variation in the centrifugal pressure differential independently of the speed of rotation.

9. A centrifugal pump comprising a rotatable housing having a series of axially aligned impeller chambers eccentrically located therein, an impeller rotatably mounted in each of said chambers and having radial passages connected together at their inner ends, fluid inlet and outlet ports at the periphery of each chamber on its two halves respectively which are opposed in a radial direction with respect to the axis of rotation of said housing, passages in said housing connecting said chambers in series, driving means for rotating said housing, and connections from said driving means for rotating said impellers, whereby a centrifugal pressure differential is obtained at the periphery of each chamber in its opposite halves causing a flow through said series of chambers.

10. A centrifugal pump as defined in claim 9, wherein said impellers are all driven by a common shaft.

11. A centrifugal pump as defined in claim 9, wherein alternate impellers are driven in opposite directions, whereby the inlet and outlet ports of consecutive chambers will be on the same halves thereof, requiring short passages to connect said chambers in series.

12. A centrifugal pump as defined in claim 11, wherein the alternate impellers are driven by a common shaft, each of said shafts having a planetary gear mounted thereon as a part of said connections, which further include a stationary sun gear and a stationary internal ring gear mounted on the axis of rotation of said housing, and meshing with said planetary gears respectively.

13. A centrifugal pump as defined in claim 9, wherein said housing is hingedly mounted on a rotatable support, and means for adjusting the housing about said hinge to vary the radial displacement of said impellers relative to the axis of rotation of said support and thus cause a variation in the centrifugal pressure differential independently of the speed of rotation.

14. A centrifugal pump as defined in claim 11, wherein said housing is hingedly mounted on a rotatable support, and means for adjusting the housing about said hinge to vary the radial displacement of said impellers relative to the axis of rotation of said support and thus cause a variation in the centrifugal pressure differential independently of the speed of rotation.

15. A centrifugal pump as defined in claim 14, wherein the alternate impellers are driven by a common shaft, each of said shafts having a drive gear at one end of said housing, a pair of planetary gears mounted on said hinge, each planetary gear being geared to one of said drive gears, a stationary sun gear on the axis of rotation of said support meshing with one of said planetary gears, and a stationary internal ring gear on the same axis meshing with the other of said planetary gears.

16. A centrifugal pump as defined in claim 15, having additional housing similarly mounted on additional hinges on said support at circumferentially spaced intervals for common operation by a single sun gear and a single ring gear, the series of chambers in all the housings being connected in series by passages through said support connecting the outlet port of the last chamber in one series to the inlet port of the first chamber in the next series; and connecting linkages between said adjusting means for simultaneous adjustment of all said housings about their hinges.
